(57) **CLAIM**

The ornamental design for a sleeve for a beverage container as shown and described.

DESCRIPTION

FIG. 1 is a top perspective view of a sleeve for a beverage container shown in an environment of use.

FIG. 2 is a top perspective view of the sleeve for a beverage container.

FIG. 3 is a bottom perspective view thereof.

FIG. 4 is a front view thereof.

FIG. 5 is a back view thereof.

FIG. 6 is a right side view thereof.

FIG. 7 is a left side view thereof.

FIG. 8 is a top view thereof; and,

FIG. 9 is a bottom view thereof.

The beverage container shown in broken lines in FIG. 1 illustrates environment that forms no part of the claimed design. All other broken lines show portions of the sleeve for a beverage container and form no part of the claimed design.
